UNITED STATES PATENT OFFICE

IGNATIUS J. VETTER, OF NEW YORK, N. Y., ASSIGNOR TO BIGELOW SANFORD CARPET CO., INC., A CORPORATION OF MASSACHUSETTS

DESIGN FOR A CARPET

Application filed September 30, 1932. Serial No. 45,177. Term of patent 7 years.

To all whom it may concern:

Be it known that I, IGNATIUS J. VETTER, a citizen of the United States, residing at New York, in Bronx County, and State of New York, have invented a new, original, and ornamental Design for a Carpet, of which the following is a specification, reference being had to the accompanying drawing, forming part thereof.

The drawing illustrates a portion of a carpet showing my design. The dot and dash

I claim:

The ornamental design for a carpet substantially as shown and described.

IGNATIUS J. VETTER.
